UNITED STATES PATENT OFFICE.

FRANK A. LUNDQUIST, OF CHICAGO, ILLINOIS, ASSIGNOR TO HENRY S. CONRAD, OF KANSAS CITY, MISSOURI.

AUTOMATIC TELEPHONE SYSTEM.

Application filed July 14, 1922, Serial No. 574,987. Renewed December 16, 1925.

The present invention relates in general to automatic telephone systems, but is more particularly concerned with systems of this character in which pneumatically operated switches are employed to complete connections between calling and called subscribers' lines.

An object of the invention is to produce an air driven selector switch of simplified mechanical construction and having novel controlling circuits.

There are other objects of the invention, which, together with the above, will be described hereinafter, reference being had to the accompanying drawings forming part of this specification.

Referring now to the drawings comprising Figs. 1-3, inclusive, there is shown by means of the conventional circuit and mechanical diagrams a connection from the line of the substation A through the line switch C, the first selector E, the connector H, to the line of the substation A'.

Referring now more particularly to Fig. 1, the substation A is of the usual automatic type, the line of which terminates at the exchange in the individual line or trunk selecting switch C.

The line switch C is a pneumatically operated switch which is very similar to the line switch disclosed in Fig. 1 of the drawings in Patent No. 1,495,755, issued May 27, 1924. Reference is made to that application for a complete description of the mechanism. The line switch C has access to trunk lines, such as the one shown in the drawings comprising conductors 178, 195 and 192, which extend to first selector switches, the first selector E, in this instance.

The selector E, Fig. 2, is a pneumatically operated switch of the vertical and rotary type. The construction and circuits of the switch are so arranged that the sylphon which controls the vertical operation of the switch is normally in an operated position. The selector E has access to trunk lines extending to connector switches, one of these trunk lines being shown in the drawings extending to the connector switch H, Fig. 3.

The connector H is an air operated switch of the same type as that disclosed in Fig. 3 of the drawings in the patent above cited to which reference is made for a complete description.

Having briefly described the apparatus

shown in the drawings, its detailed operation will now be explained. For this purpose it will be assumed that the subscriber at substation A desires to extend a connection to the line of the substation A'. In order to do this the calling subscriber will remove his receiver and operate his calling device in accordance with the digits of the called subscriber's number.

When the receiver is removed a circuit is completed for the magnet 33 extending as follows: battery X, upper winding of relay 33—172—173—174—171—substation A—170—175—175^a—175^b—lower winding of relay 33 to ground. This causes magnet 33 to attract its armature 34, to first open valve 35 and to then close springs 180 and 181. Opening valve 35 admits air to motor 20 which immediately rises, carrying its wipers on a trunk hunting movement over the bank contacts shown above them, and permitting spring 301' to engage spring 302'. When the wiper 179 reaches a contact which has a ground connection, as for example, the contact associated with conductor 178, a circuit is completed as follows: ground in the selector E, resting contact of spring 313 and said spring, through the winding of coil 301, springs 370, conductor 178—179—182—24—183—180—181—186—184—184^a—185 to battery.

This operates magnet 24 to throw pawl 26 into the ratchet teeth 23 and to stop the upward movement of the motor 20 with its wipers on the terminal of the selected trunk. The attraction of the armature 25 by the magnet 24 also opens the valve 28 to admit compressed air to the sylphon 32. The operation of this sylphon shifts the adjacent contact springs to their alternate position and also moves the lever 200 to throw the pawl 27 onto the teeth 22 and to close springs 187 and 188. When the sylphon 32 shifted the adjacent contact springs it opened the circuit for the magnet 33 at 174 and 175, and at the same time caused these springs to operate springs for completing a circuit through to the line relay 300 of the selector. When the circuit is broken for magnet 33, the armature 34 falls back to open the circuit for the magnet 24 but the lever 200 previously closed springs 187 and 188 so that a locking circuit is maintained by the branch from 183 by way of 188—187—302'—184—184^a—202 to ground. When the armature 34

falls back it permits valve 35 to close, with the result that air becomes exhausted in the motor 20. The pawl 27, however, holds the motor 20 against falling, and will continue 5 to hold it as long as the sylphon 32 continues to receive air through valve 28.

The magnet 301 in the selector E was energized over the above traced circuit and by attracting its armature 310 opened the valve 311 to permit air to be supplied to the sylphon 307. The sylphon 307 operates to allow the vertical and rotary pawls 318 and 319, respectively, to engage their associated ratchet wheels by operating the shaft 317. 10 The operation of the sylphon 307 also causes the bell crank lever 312 to operate spring 313 thereby transferring the connection of conductor 178 from ground to battery. By the 15 jockey pin arrangement of the bell crank lever the spring 313 is locked in engagement with its working contact. As the operation of the sylphon 32 in the line switch C shifts the connections of the magnet 24 from battery to ground the line switch C is maintained in operated position.

The operations above described result in connecting the line of the substation A to the line relay 300 of the selector E over a circuit which extends as follows: Ground 30 through the left hand winding of relay 300, resting contact of spring 330 and the said spring, conductor 195—196—197—189—174—171—substation A—170—175—189'—190—192, spring 331 and its resting contact, and through the right hand winding of the line relay 300 to battery. Relay 300 operates over this circuit and attracts its armature 354 thereby closing valve 355 whereby the air supply is disconnected from 40 the sylphon 306. Sylphon 306 immediately becomes inoperative thereby allowing the spring 335 to operate the pawl 334 to raise the switch shaft a partial step into such position as to be operated by the subsequent 45 operations of the sylphon 306. The sylphon 303 also restores to normal after a short interval. However, its operation is without function at the present time as the shaft of the switch has not yet been operated opposite the first level of bank contacts. The armature 371 on the line relay 300 is of the slow releasing type and is immediately operated when the relay is energized. The 50 operation of armature 371 closes a shunt path around the off normal springs 370 at springs 367 so as to provide against opening the holding circuit which extends back to the line switch C when the off normal springs are operated, which occurs shortly 55 after the operation of relay 300, when the switch shaft is given its preliminary step.

The operations above described all take place automatically in response to the removal of the receiver at substation A.

65 The subscriber at substation A is pre-

sumed to have an ordinary calling device at his local station, the operation of which breaks and then remakes the line circuit a desired number of times. The rapidity with which the circuit is broken and remade is presumed to be too great to permit the sylphon 303 or the armature 371 to retract so that the only thing for immediate consideration in response to the operation of the calling device is the actuation of armature 354.

Upon the first break and remake of the circuit through magnet 300, armature 354 is retracted and then attracted. In falling back the armature 354 opens the valve 355 and permits air to flow through the pipes 343 and 344 to the sylphon 306 and also to the slow sylphon 303. Upon being attracted again, air is cut off from the motors 306 and 303. As the armature 354 vibrates back and forth in response to the breaks and remakes of the circuit of the local station the motor 306 responds and moves with these pulsations but the motor 303 is made slow acting by the check valve 309 and remains in operated position. Each time the sylphon 306 deenergizes it allows the spring 335 to actuate the pawl 334 thereby raising the switch shaft carrying the switch wipers 350—352, inclusive, step by step until they are placed opposite the proper level of bank contacts as determined by the number of interruptions in the digit dialled. Upon the first step of the switch shaft, the lever 357 is operated under influence of the spring 322 and raises so that when the sylphon 303 becomes inoperative it will actuate the lever 358. Shortly after the termination of the vertical movement of the switch the slow acting sylphon 303 becomes inoperative thereby operating the lever 358. This operation closes the valve 321 thereby permanently shutting off the supply of air to the pipe 344 so as to maintain the sylphon 306 deflated and also opens the valve 320 thereby allowing air to be supplied to the sylphon 305. Sylphon 305 operates through the medium of the pawl 337 to rotate the switch shaft carrying the wipers in on the first set of bank contacts. The operation of the lever 342 causes the valve 339 to be closed thereby shutting off the supply of air to the sylphon 305 which immediately deflates and operates the valve 339 to again allow air to be supplied to the sylphon 305. In this manner the switch wipers are automatically rotated until engagement is made with a set of bank contacts associated with an idle trunk line. Assuming that the trunk line shown in the drawings comprising conductors 360—362, inclusive, is the first idle trunk line, then, when the switch wipers are brought into engagement with the associated bank contacts a circuit is completed extending from ground, Fig. 3, springs 207

and 208, conductor 209, conductor 360, wiper 350, coil 302, spring 332 and its resting contact to battery. Magnet 302 is energized over the above circuit and attracts its armature 338 to stop the rotary trunk hunting operation by permanently closing valve 339.

A further result of the operation of magnet 302 is that at armature 350 the valve 355 is opened thereby admitting air to the slow sylphon 304. The operation of the sylphon 304 disconnects the incoming trunk conductors 195 and 192 from the windings of the line relay 300 and extends them over wipers 351, 352, trunk conductors 361, 362, through the windings of the line relay 112-113, of the connector H. By the operation of spring 332, controlled by the sylphon 304, the test wiper 350 is disconnected from battery and connected through a resistance to ground. The deenergization of the line relay 300 merely prepares certain releasing circuits as will subsequently appear.

In the connector H the line relay 112-113 is energized and operates its armature 115 to allow air to flow to the motor 118. Motor 118 is made slow acting by means of a check valve, as shown, and by the operation of spring 208 it connects the test connector 209 to battery whereby a holding circuit is established for the coil 302 of the selector E.

The attraction of armature 114 of the line relay causes the valve 116 to close the other end of the pipe 231, of the line relay armatures. Armature 114 responds to impulses through the magnet 112-113 while 115 is a slow armature which does not respond to such impulses but remains attracted until the break of the circuit through the magnet is of longer duration than occurs in the calling device.

The motor 118 also raises the lever 119 to engage the pin on disc 134 directly above its right hand end, and as the motor 118 continues to rise, the disc 134 is rotated by the lever 119 far enough for the pin 137 to operate lever 140 to open the valve 142 and to permit compressed air to flow to the motor 127 which puts a horizontal strain on the carriage 124. In this operation the disc 134 is advanced so as to bring one of its teeth nearer to the pawl 150. It also permits pawl 146 to engage the disk 134.

The operations above described are automatic ones consequent to the selector finding an idle connector. When the subscriber again operates his calling device, the consequent vibrations of armature 114 open and close valve 116 to permit pulsations of air to flow from pipe 231 through pipe 232 to slow motor 233 and to the escapement motor 121. The motor 233 opens valve 234 to permit air to flow to motor 147, and keeps air on motor 147 as long as successive impulses flow through magnet 112-113. The operation of motor 147 lifts rod 148 and brings

pawl 150 adjacent to the first tooth or notch in disk 134. It also shifts certain electrical connections to be described later.

The movement of disk 134 by motor 118 turned the rack 122 to engagement with the tail 132 of the pawl 130 so that the pulsations going to motor 121 will operate said pawl to permit the carriage 124 to move under strain of motor 127. At the termination of the series of electrical impulses coming as the result of the operation of the calling device, the armature 114 remains in attracted position and the valve 116 closes. Closing valve 116 shuts air from motor 233 which in turn shuts air from motor 147 which falls back. This permits spring 153 to force rod 148 downward. In this movement, the pawl 150 engages the disk 134 to rotate it one step, the effect of which is to turn the rack 122 from engagement with the tail 132 of the pawl 130 into engagement with the lower end of a T-shaped lever as shown in Fig. 11 of my patent previously mentioned. The T-shaped lever is pivoted at its upper end at the intersection of the horizontal portion and the vertical portion of the T. On each end of the horizontal portion of the T a pawl is pivoted for engaging in the teeth of a rack which is attached to the wiper carriage. By the movement of the T-shaped lever to its forward position one of the pawls is operated to engage and move the rack vertically a half step and on the movement of the T-shaped lever to normal position the other pawl engages and moves the rack another half step, thus raising the wiper a full step for each complete operation of the T-shaped lever.

When the subscriber operates his calling device to send a second series of impulses to this connector, motors 147 and 121 are operated as before. This time the reciprocations of the rack 122 move the carriage upward until the wipers carried thereby are on contact terminals which represent the subscriber to be called. At the termination of these impulses, the motor 147 and the rod 148 fall to advance the disk 134 another step which carries the rack 122 beyond and clear of the T-shaped lever.

It will be assumed that the connector stops on the lower right hand bank contacts shown in Fig. 3 and that the wires leading from these contacts are the wires shown leading to the line switch of the called line, indicated by the reference character C'. It will be understood that this line switch is similar to the line switch shown in Fig. 1 in all respects. When engagement is made with this set of bank contacts the rod 148 is in elevated position but as soon as there is a pause in the impulses which move the connector to its desired position the motor 147 and the rod 148 fall back whereupon the circuit is completed as follows: battery F 180

at the upper left hand part of Fig. 3, 241—242—private wiper 244—245—normal wire 246, to the line switch shown, after which the circuit may be traced as follows, reference being had to the line switch of Fig. 1: 247—251—179—182—24—183—180—250—249—248 to ground. The magnet 24 of the called line switch is energized over this circuit which magnet throws the pawl 26 into the teeth on the motor 20 to lock the called line switch against displacement. Magnet 24 also opens valve 28 to admit air to the sylphon 32 thereby shifting the adjacent contact springs. The complete talking circuit is shown in heavy lines.

The signalling circuit has been omitted in order to avoid complications, and because it is not necessary to a full understanding of the invention. It may be any well known adaptation of ordinary devices to the present arrangement.

The previous description assumed that the line switch of the called station was in normal position. If, however, that line switch had been moved from its normal position by the subscriber calling, then the terminals of the normal wires would be opened and the connector would be unable to make connection with the called line.

It was assumed that the called station had not been connected with by some other party. If we assume that a connector switch is in engagement with the bank contacts associated with the called line when the wipers of the connector H are brought into engagement with the set of multiple contacts, the rod 148 would be in its elevated position. Under these conditions a circuit will be completed as follows: from battery on the test contact of a called line where it has been placed by the precedingly operated connector, test wiper 244—242—266—coil 267—268—269—270 to ground. The magnet 267 is energized over this circuit and operates its armature 272 to move the bell crank 273 away from the rod 148 so that when the said rod falls it will not close the circuit for wipers 262 and 256 at the adjacent contact springs. The bell crank 273 is pivoted on the horizontal lever shown just to the right of the intersection of its vertical and horizontal arms. The spring shown near the left hand end of this bell crank is arranged to normally hold the vertical arm of the bell crank 273 in such a position that the hook on its lower end will be in position to be engaged by the horizontal arm of the rod 148 when the rod 148 returns to normal position. By the energization of magnet 267, however, the hook on the end of the bell crank 273 has been pivoted far enough away from the horizontal arm of the rod 148 so that the descent of the rod 148 does not operate the springs 265, 264, 253, 254, 270 and 269. The busy signal which would result

from this combination of operations is omitted for the sake of simplicity and also for the reason that it is unnecessary for an understanding of how connections are made from one station to another.

When the subscriber at the calling station hangs up his receiver he opens the circuit of the magnet 112—113 of the connector. This permits the armatures of this magnet to fall back. The restoration of armature 115 closes the valve 117 and shuts off the supply of air from the motor 118 which falls back. By this operation the holding circuit extending back to the magnet 302 in the selector E is opened. Another result of the motor 118 returning to normal is that it releases pawl 146 so that the disk 134 and associated parts return to normal. Reference is here made to the before cited application for a detailed description of the connector release. It will suffice to say that the above release of the line relay causes the connector H to be restored to normal.

The release of the connector also disconnects battery from the test contact of the called line whereupon the magnet 24 therein deenergizes to restore the circuits of the called line switch to normal.

The deenergization of the magnet 302 in the selector E releases armature 350. Armature 338 is not released as it is mechanically locked up until the shaft restores to normal. Upon falling back, armature 350 closes valve 355 whereby air is disconnected from the sylphon 304.

It will be noted that armature 350 upon falling back opens the springs 368. The holding circuit for the magnet 301 in the selector E and the magnet 24 in the line switch C is now opened. The sylphon 304 restores to normal thereby allowing the associated springs to assume their normal position. The magnet 301 deenergizes as its holding circuit is opened thereby allowing the sylphon 307 to deflate. The pawls 318 and 319 are thereby withdrawn from engagement with the shaft, the latter immediately restoring to normal. When the shaft reaches its normal position it actuates the levers 340 and 357. The operation of the lever 340 allows the armature 338 on the coil 302 to retract. The operation of the lever 357 causes the lever 312 to assume its normal position thereby letting spring 313 engage its resting contact. In this manner the selector E is restored to normal.

In the line switch C the relay 24 deenergized to remove the holding pawl 26 from the motor 20. Another result of the deenergization of relay 24 is that the supply of air is cut off from the sylphon 32. The sylphon 32 deflates thereby allowing the adjacent contact springs to assume their normal position and removing the pawl 27 from the motor 20 to permit its restoration.

In the above manner the connection is released responsive to the replacement of the receiver at both substations. It is to be noted that this release does not occur until

5 both calling and called subscribers replace their receivers. That is, the last party to hang up causes the release of the connection.

10 The features of the invention having been described and ascertained, what is considered to be new and desired to have protected by Letters Patent will be pointed out in the appended claims.

What I claim as my invention is:—

15 1. In a telephone system, an automatic switch having a shaft adapted to move in a vertical direction, a pawl for actuating said shaft, a motor for operating said pawl, said motor normally being in an operated position, a line relay for said switch, and means for energizing said line relay to cause said motor to become deenergized.

20 2. In a telephone system, an automatic switch having a shaft, a pawl for actuating said shaft, a motor for operating said pawl, said motor normally being in an operated position, a line relay for said switch, and means for energizing said line relay to cause said motor to become deenergized to operate said shaft.

25 3. In a telephone system, an automatic switch having a shaft, a pawl for operating said shaft, an air motor for operating said pawl, said motor normally being in an inflated condition, a line relay for said switch, and means for energizing said line relay to cause said motor to deflate to operate said pawl.

30 4. In a telephone system, an automatic switch having a shaft, means for operating said shaft vertically, means for rotating said shaft, a slow acting device normally energized, a line relay for said switch, and means for energizing said line relay to deenergize said device at the end of the vertical operation of said shaft to initiate the operation of said rotary operating means.

35 5. In a telephone system, an automatic switch having a shaft, a pawl for operating said shaft, an air motor for operating said pawl, said motor normally inflated, a line relay for said switch, means for energizing said line relay to deflate said motor to operate said shaft, and means for maintaining said motor deflated after said shaft is operated.

40 6. In a telephone system, an automatic switch having wipers, trunk lines accessible to said wipers terminating in contacts arranged in groups, means for operating said wipers vertically step by step opposite a desired one of said groups, an interrupter in said switch consisting of a pneumatic motor and an air valve arranged to control each other to operate the motor for rotating the wipers into engagement successively

with the contacts of the desired group, means for automatically initiating the operation of said interrupter after the vertical movement of said wipers, a magnet arranged to have its circuit closed by one of the wipers when engaging with the contact of an idle trunk line, and means actuated by said magnet for arresting the advance of said wiper.

45 7. In a telephone system, an automatic switch having wipers, trunk lines accessible to said wipers terminating in contacts arranged in groups, means for operating said wipers vertically step by step opposite a desired one of said groups, an interrupter in said switch consisting of a pneumatic motor and an air valve arranged to control each other to operate the motor for rotating the wipers into engagement successively with the contacts of the desired group, means for automatically initiating the operation of said interrupter after the vertical movement of said wipers, a magnet arranged to have its circuit closed by one of the wipers when engaging with the contact of an idle trunk line, and means actuated by said magnet for arresting the advance of said wiper, and for completing the connection to said idle trunk line.

50 8. In a telephone system, an automatic switch having primary and secondary movements, trunk lines terminating in said switch divided into groups, wipers on said switch for engaging with the terminals of said trunk lines, means for operating said switch step by step in its primary movement to select a desired one of said groups, a pneumatic motor for operating said switch step by step in its secondary movement, a source of air pressure, means for automatically initiating the operation of said motor after said primary movement, means operated by said motor for thereafter intermittently interrupting its own source of air pressure to operate said switch step by step in its secondary movement, a magnet in said switch, means for energizing said magnet when one of the wipers engage with an idle one of said trunk lines, and means operated by said magnet for stopping the operation of said motor and arresting the movement of said switch.

55 9. In a telephone system, an automatic switch having primary and secondary movements, trunk lines terminating in said switch and divided into groups, means for operating said switch step by step in its primary movement to select a desired one of said groups, a pneumatic motor for operating said switch in its secondary movement, a source of air pressure, means for initiating the operation of said motor after said primary movement, and means operated by said motor for thereafter intermittently interrupting its own source of air pressure

- to operate said switch step by step in its secondary movement to select an idle one of said trunk lines.
10. In a telephone system, an automatic switch having primary and secondary movements, means for operating said switch step by step in its primary movement, a pneumatic motor for operating said switch in its secondary movement, a source of air pressure, means for operating said motor, and means thereafter operated by said motor for intermittently interrupting its own source of air pressure to operate said switch step by step in its secondary movement.
15. 11. In a telephone system, an automatic switch having primary and secondary movements, means for operating said switch in its primary movement, a slow acting device for said switch normally energized, a line relay for said switch, a motor for said switch, a source of power for said motor, means for energizing said line relay to de-energize said device at the end of the primary movement to initiate the operation of
20. 25. said motor, and means thereafter operated by said motor for intermittently interrupting its own source of power to operate said switch step by step in its secondary movement.
30. 12. In a telephone system, an automatic switch having primary and secondary movement, a motor for said switch, said motor normally being energized, a line relay for said switch, means for intermittently en- ergizing and deenergizing said relay to cause
35. 40. 45. said motor to move said switch step by step in its primary movement, a change-over motor for said switch, said change-over motor normally being energized, a third motor for said switch, a source of power for said third motor, means controlled by said relay after said primary movement for de-energizing said change-over motor, means controlled by the deenergization of said change-over motor to initiate the operation
- of said third motor, and means thereafter operated by said third motor for intermittently interrupting its own source of power to operate said switch step by step in its secondary movement.
13. In a telephone system, an automatic switch having primary and secondary movements, a motor for operating said switch step by step in its primary movement, said motor normally being energized, a line re- lay for said switch, means for operating said switch in its primary movement and for energizing said line relay to deenergize said motor at the end of the primary move- ment, a second motor for operating said switch in its secondary movement, a source of power, means for operating said second motor, and means thereafter operated by said second motor for intermittently inter- rupting its own source of power to operate said switch step by step in its secondary movement.
14. In a telephone system, a switch hav- ing primary and secondary movements, trunk lines, means for operating said switch step by step in its primary and secondary movements to connect with an idle one of said trunk lines, off-normal springs for said switch, a line relay in said switch for controlling the operation of said switch in its primary movement, a switching relay in said switch for completing the connection to said idle trunk, a release relay in said switch energized at the time said switch is seized for maintaining said switch in its operated position, and circuit arrangements whereby said release relay is initially energized through said off-normal springs and subse- quently and consecutively maintained en- ergized first, solely by said line relay and second solely by said switching relay.

Signed at Chicago, Illinois, this 24th day of June, 1922.

FRANK A. LUNDQUIST.
